UNITED STATES PATENT OFFICE.

WILLIAM V. ROBBINS, OF BLOOMSBURG, PENNSYLVANIA.

DESIGN FOR A POST CAP OR FINIAL.

SPECIFICATION forming part of Design No. 24,057, dated February 19, 1895.

Application filed December 13, 1894. Serial No. 531,736. Term of patent 7 years.

To all whom it may concern:

Be it known that I, WILLIAM V. ROBBINS, a citizen of the United States, and a resident of Bloomsburg, in the county of Columbia and State of Pennsylvania, have invented certain new and useful Improvements in a Design for a Post Cap or Finial; and I do declare the following to be a full, clear, and exact description of the invention, such as will enable others skilled in the art to which it appertains to make and use the same, reference being had to the accompanying drawing, and to letters of reference marked thereon, which forms a part of this specification.

The figure of the drawing is a representation of the invention.

This invention has relation to a certain new and useful design for post caps or finials, and it consists in the novel form and configuration of parts, all as hereinafter described and illustrated in the accompanying drawing.

The leading feature of the design consists

in a hollow cylindric base portion A which merges upwardly into a finial representing in general form the figure of a horned owl. Said finial is formed with projections or raised portions which resemble feathers, some of which overlie the upper part of the base portion A.

a, a, indicate the feather like projections which form the horns of the figure of the owl.

The design not only forms an ornamental post cap or finial, but may be employed in the neighborhood of gardens and fruit trees for its effect upon chickens and birds.

What I claim is—

The design for post caps or finials substantially as herein shown and described.

In testimony whereof I affix my signature in presence of two witnesses.

WILLIAM V. ROBBINS.
